UNITED STATES PATENT OFFICE

152,125

DESIGN FOR A COMBINATION RECORD PLAYER AND RADIO

Clyde A. Peterson, Lewisburg, Pa., assignor to
Westinghouse Electric Corporation, a corpora-
tion of Pennsylvania

Application August 22, 1946, Serial No. 132,731

Term of patent 7 years

(Cl. D56—4)

To all whom it may concern:

Be it known that I, Clyde A. Peterson, a citizen of the United States, residing at Lewisburg, in the county of Union and State of Pennsylvania, have invented a new, original, and ornamental Design for a Combination Record Player and Radio, of which the following is a specification, reference being had to the accompanying drawings, forming a part thereof, in which:

Fig. 1 is a front perspective view of a combination record player and radio, embodying my new design, with the closure element in elevated position,

Fig. 2 is a front perspective view of the apparatus shown in Fig. 1 with the closure element in down position, and

Fig. 3 is an exploded front perspective view of the apparatus shown in Figs. 1 and 2.

The right-hand portions in all figures are similar in appearance to the ends shown in the drawings. The rear portions are plain.

The dominant features of my new design are shown by means of full lines in the drawings.

I claim:

The ornamental design for a combination record player and radio, substantially as shown and described.

CLYDE A. PETERSON.
